UNITED STATES PATENT OFFICE

110,383

DESIGN FOR A TRIM FOR A DOOR OR WINDOW FRAME OR THE LIKE

Dwight J. Baum, New York, N. Y., assignor to
Curtis Companies Incorporated, Clinton, Iowa,
a corporation of Iowa

Application October 18, 1937, Serial No. 72,255

Term of patent 7 years

To all whom it may concern:

Be it known that I, Dwight J. Baum, a citizen of the United States and a resident of New York, in the county of Bronx and State of New York, have invented a new, original, and ornamental Design for a Trim for a Door or Window Frame or the Like, of which the following is a specification, reference being had to the accompanying drawing, forming part thereof.

Figure 1 is a front elevation of a trim for a

door or window frame or the like showing my new design; and

Figure 2 is a vertical sectional view taken on the line 2—2 of Figure 1.

I claim:

The ornamental design for a trim for a door or window frame or the like substantially as shown.

DWIGHT J. BAUM.
